UNITED STATES PATENT OFFICE.

ETHAN I. DODDS, OF PITTSBURGH, PENNSYLVANIA, ASSIGNOR TO FLANNERY BOLT COMPANY, OF PITTSBURGH, PENNSYLVANIA.

STAY-BOLT STRUCTURE.

1,293,369.

Specification of Letters Patent.

Patented Feb. 4, 1919.

Application filed April 26, 1918. Serial No. 230,915.

To all whom it may concern:

Be it known that I, ETHAN I. DODDS, a citizen of the United States, and a resident of Pittsburgh, in the county of Allegheny and State of Pennsylvania, have invented certain new and useful Improvements in Stay-Bolt Structures; and I do hereby declare the following to be a full, clear, and exact description of the invention, such as

10 will enable others skilled in the art to which it appertains to make and use the same.

This invention relates to improvements in staybolt structures for boilers and more particularly to the devices for securing the closure on the end of the bearing sleeve,—the object of the invention being to provide means whereby the cap or closure may be quickly removed from the bearing sleeve to expose the head of the staybolt for testing purposes; so that it may be as quickly replaced and so that the cap or closure will be normally held firmly to its seat on the bearing sleeve.

With this and other objects in view, the invention consists in certain novel features of construction and combinations of parts as hereinafter set forth and pointed out in the claims.

In the accompanying drawings, Figure 1 is a longitudinal sectional view of a staybolt structure showing an embodiment of my invention. Fig. 2 is a side elevation partly in section. Fig. 3 is a transverse section of the locking head. Fig. 4 is a bottom plan view of said locking head. Fig. 5 is a plan view of the cap or closure. Fig. 6 is an edge view of the cap or closure, and Fig. 7 is a view of a modification.

1 represents a bearing sleeve having an interior curved face 2 constituting a bearing for the head 3 of the staybolt 4.

The outer end portion of the bearing sleeve 1 is provided exteriorly with a plurality of inclined shoulders 5 forming cams. 45 A cap or closure 6 is seated against the end portion of the bearing sleeve and has a general partly spherical shape with its interior dimensions and configuration such as will afford a suitable clearance space 7 for the 50 head of the staybolt.

A locking head or carrier 8 incloses the cap or closure 6 and provided with an angular exterior portion 9 to receive a wrench. The rear edge of the portion 9 of the head or

carrier 8 is provided with interior segmental shoulders 10 which are beveled or inclined to form cams to coöperate with the cam shoulders 5 on the bearing sleeve.

The head or carrier 8 is provided on its inner face near the peripheral flange 9 with a plurality of cam faces 12 to coöperate with cam lugs or shoulders 13 projecting laterally from the cap or closure as shown in Fig. 5. In Fig. 7 three such lugs are shown.

The cap or closure 6 is loosely connected with the head or carrier 8 by means of a split ring 14 mounted in a groove within the flange portion 9 of the head or carrier and underlying the cam lugs or shoulders of the cap or closure.

The parts, assembled as above explained, are applied to the end of the bearing sleeve so that the cap or closure will rest on its seat and then the head or carrier will be turned so as to cause the cam shoulders 10 to become disposed behind and engage the cam shoulders 5 on the bearing sleeve and at the same time or immediately after the cam shoulders 10 have engaged the cam shoulders 5, a slight movement of the head or carrier relatively to the cap or closure will cause the coöperation of the cams 12—13 to force the cap or closure tightly against its seat. It will be seen that with the use of my improvements, the cap or closure will be held firmly against its seat and that the binding of the cams 5 and 10 will hold the head or carrier securely to the bearing sleeve. It is apparent that by a reversal of the operations above described, the cap and its carrier will be unlocked from the bearing sleeve and may be quickly removed to expose the head of the bolt for testing purposes.

Having fully described my invention what I claim as new and desire to secure by Letters-Patent, is:

1. In a staybolt structure, the combination with a bearing sleeve and a cap or closure to seat thereagainst, of a head or carrier inclosing the cap or closure, cam lugs or shoulders projecting laterally from said cap or closure, cams within the cap or closure to coöperate with said cam lugs or shoulders, a split ring mounted in the head or carrier and underlying said cam lugs or shoulders of the cap or closure, and means removably connecting the head or carrier with the bearing sleeve.

2. In a staybolt structure, the combination with a bearing sleeve and a cap or closure to seat thereagainst, said cap or closure having a plurality of lateral lugs or shoulders, of a 5 head or carrier inclosing the cap or closure and having an internal groove, a split ring underlying said lateral lugs or shoulders of the cap, segmental cam shoulders on the bearing sleeve, and segmental cam shoulders 10 within the rear portion of the head or car-

rier and adapted to coöperate with the segmental cam shoulders on the bearing sleeve.

In testimony whereof, I have signed this specification in the presence of two subscribing witnesses.

ETHAN I. DODDS.
